UNITED STATES PATENT OFFICE.

IRVING L. KORROL, OF BROOKLYN, NEW YORK.

SAFETY WINDOW CONSTRUCTION.

Application filed November 24, 1923. Serial No. 676,682.

To all whom it may concern:

Be it known that I, IRVING L. KORROL, a citizen of Russia, but having declared my intention of becoming a citizen of the 5 United States, residing at New York city, borough of Brooklyn, in the county of Kings and State of New York, have invented certain new and useful Improvements in Safety Window Constructions of which the 10 following is a specification.

This invention relates to building constructions and has particular reference to window mechanism of the usual vertical sliding sash style.

15 Among the objects of the invention is to provide improved means for giving access to the outer surfaces of window sashes, for cleansing, polishing, or other like purposes, without requiring the person to go or reach 20 beyond the plane of the window, thereby making it safe and convenient for each entire sash to be cleansed and polished while the operator is stationed entirely within the room. I am aware that structures for 25 this general purpose have been proposed heretofore, but among the objects I attain are the following: To make it easy for both of two co-operating sashes to be manipulated readily in the manner already stated, means 30 being provided to disconnect one of the sash cords from each sash so as to permit the window sash to swing or be drawn inward around the opposite edge thereof as an axis for cleansing or removal and then for it to be returned and the sash cord reconnected both easily and quickly; to provide 35 means for removing the upper and normally outer sash whether the lower sash is removed from the window or not, an expedient not heretofore provided for so far as I am aware; also to provide means for 40 removing easily both sashes from the window for maximum ventilation or other purposes, the disconnecting means for the sash cords being both operated simultaneously by a single simple mechanical movement, and I provide means also for locking both window sashes to each other in such a manner 45 as to make it impossible for either sash to be moved, the locking means being hidden within the window frame.

50 With the foregoing and other objects in view the invention consists in the arrangement and combination of parts hereinafter described and claimed, and while the invention is not restricted to the exact do-

tails of construction disclosed or suggested herein, still for the purpose of illustrating a practical embodiment thereof reference is had to the accompanying drawings, in 60 which like reference characters designate the same parts in the several views, and in which—

Figure 1 is a front elevation of my improved window construction as viewed from 65 the inside, the window frame being shown open to give access to the mechanism, and portions being broken away at the top.

Fig. 2 is a horizontal section on the line 70 2—2 of Fig. 1.

Fig. 3 is a vertical section on the line 75 3—3 of Fig. 4 but with certain of the parts in moved position.

Fig. 4 is a horizontal section on the line 80 4—4 of Fig. 3.

Fig. 5 is an enlarged vertical detail corresponding to a part of Fig. 3 and with certain parts in moved position indicated in dotted lines.

Fig. 6 is a horizontal section on the line 85 6—6 of Fig. 3.

Fig. 7 is a diagram indicating the window construction with the lower sash swung inward and supported in such position.

Fig. 8 is a detail view taken from about 90 the line 8—8 of Fig. 1.

Figs. 9 and 10 are detail views of the preferred means for disconnecting the normally connected sash cord so as to remove entirely the window sash from the window.

Fig. 11 is a detail of the sash lock. Referring now more specifically to the drawings I show a window frame having 95 right and left sides 10 and 11, a top 12 and a bottom or sill 13. The stiles 10 and 11 are made hollow as usual for the accommodation of the vertically slideable sash weights 14 connected by cords or the like 15 to the respective upper and lower sashes 16 and 17. According to the showing the weights for 100 the right side of the window operate over simple pulleys 18, while those at the left side operate over double pulleys 19 journaled in brackets 20 which extend far enough laterally to guide the weights to operate in a plane farther from the sashes than usual. The counterweighting effect of the weights 14 on the several sashes is as usual during the up and down sliding movements of the sashes. Within the top 12 of

105 the frame is arranged a cap 21 connected at 110

its ends to a pair of arms 22 and 23, the rear ends of which are pivoted at 24, the cap being movable upward by impact of the top of the lower sash 17 for the purpose of 5 permitting free forward removal of the upper sash at the bottom of the window in a manner soon to be described. This upward movement of the cap 21 is resisted by means of a weight 24' attached to the arm 23.

10 The sash cords 15 are all detachably connected to the vertical side rails of the respective sashes in order to permit the manipulation of the sashes, either for cleansing or for removal thereof entirely from the 15 window frame. The cords at the right side of the window are provided each with a clip 25 having the cord secured within a stem 25^a thereof and having at or near its lower end a T-head 26, the longer axis of which is 20 parallel to the stem. The sash in its adjacent edge is provided with a recess 27 over which is secured a socket plate 28 having a transverse key hole or slot 29 to receive the head 26 therethrough when the clip is 25 turned at right angles to the window sash or its normal position. After the head is thus passed into the socket and is swung with the stem upward the head is interlocked in the socket and thus the cord is reliably 30 secured in operative position. The cords obviously may be removed easily by a reversal of the aforesaid operation when desired to detach entirely the sashes from the window.

35 At the opposite or left side of each sash is provided as shown a recess 30 in which is fitted a metallic socket member 31 having an open top and open side, the side walls of the socket being provided with open 40 ended tapered slots 32, the opening thereof being downward and flush with the side edge of the window sash and the closed upper end of each slot forming a seat for a laterally projecting lug 33 formed on or 45 carried by each side of a clip 34 for the cord 15 at that side. It will be understood from Figs. 4 and 5 that the two laterally projecting lugs 33 are adapted to be received into the socket piece 31 through the lower open 50 mouths or ends of the slots 32 and be guided upward into their seats in the side walls of said socket piece while the weight attached to the cord thereof acts to draw the same normally upward and hold it in its place.

55 The lower end of the clip 34 consists of a hook 35 the point of which projects upward and outward but still within the plane of the side edge of the window sash in normal position. These clips 34 and co-operating parts as just described in detail are provided for both the sashes. See Fig. 4.

Within the stile 11 and located between the plane of the weights and the wall 36 constituting the bottoms of the channels in 60 which the sashes are guided is located a cas-

ing 37 extending upward along the lower portion of the window frame and containing within it the principal parts of the actuating or detaching mechanism. This casing and the parts associated therewith are normally hidden from view within the side piece of the frame and access thereto is had when desired by means of a door 38 adapted to swing forward and away from the window as shown in Fig. 1. In any suitable 75 part of the casing 37 is journaled around a horizontal axis a shaft 39 journaled in brackets 40 and having on its forward end an actuating lever 41 or its equivalent projecting normally upward. 80

An actuator dog 42 projects through a slot 43 in the wall of the casing and a space or slot 44 in the wall 36 and is designed to be given both sliding and tilting movement with respect to a fixed pivot pin 45 extending through a slot 46 in the dog. The inner end of the dog is pivoted at 47 to an arm 48 fixed to the shaft 39 and constituting with the lever 41 a bell crank. The arm 48 projects normally downward and slightly away from the window sash, the pivot 47 being normally below the pin 45. The outer end of the dog consists of a downwardly projecting hook 49 which lies normally close outside the vertical plane of the edge of the window sash 95 and close above the hook 35. When it is desired to detach either clip 34 from the window sash, the sash being adjusted to a proper elevation for this purpose, the operator simply swings open the door 38, grasps the lever 41 and swings it downward to the left, and causes thereby the dog to be projected outward sliding along the pin 45 and ultimately in a clockwise partial rotation around the pin, the hook 49 passing first outward over the hook 35 and then downward into engagement with the hook 35 and so serving in the latter part of the movement of the actuator to carry the clip 34 downward and the lugs 33 out of their seats, the two hooks 35 and 49 remaining in interlocked engagement while the lever 41 remains in its down position. It will be understood that the actuators for both sash clips 34 are operated simultaneously so that either or both of them will detach the clips 34 depending upon the location of the window sashes at such time. 110

The guide channels above referred to in which the sashes slide up and down in the usual manner include on the right side as shown front, rear, and middle strips 50, 51, and 52 fixed as usual to the window frame. On the other side, however, the strips 50' and 52', particularly adjacent to the lower half of the window frame, are movable out of normal position toward or into the hollow side wall of the window frame, as shown in Fig. 6, to permit the sashes to be removed inward after the cords are detached there- 115

from as just described. Any suitable means may be provided for drawing these movable guides out of the way, and to this end I show mechanism as follows: 53 are two bell 5 cranks pivoted on vertical pivots 54 and movable simultaneously through arcs of circles around such pivots by means of a rod 55 pivoted at 56 to each of them. The front 10 end of this rod has a knob 55' projecting in front of the casing 37 and within convenient grasp of the operator after he has operated the actuator lever 41. A pair of links 57 are each connected at one end at 58 to the front end of the co-operating bell crank 53 15 and at its other or outer end it is pivoted at 59 to a bracket or plate 60 secured to the movable strip. In the normal position of the guides as shown in Fig. 2, the links 57 and adjacent or front portions of the bell 20 cranks lie in substantially a straight line, thereby locking the strips in normal projected sash holding position and the rod 55 with its knob being at this time forward. This will be understood from Fig. 6 which 25 shows the guides withdrawn from normal position and the bell cranks so swung as to break the lock just mentioned. A simple push rearward, however, of the rod 55 will swing the bell cranks around their pivots and draw the guides to the position shown 30 in Fig. 6. While these guide strips are shown coupled for simultaneous shifting movement into and out of position, it is obvious that the mechanism might be arranged so that they might be operated independently if preferred.

From the foregoing specific description of the mechanism the mode of operation may be briefly summarized as follows: With the window sashes in their normal position and guided for the usual sliding movement up and down if it be desired to polish the outer surfaces, the operator if he wishes to act upon the sashes one at a time which is the usual course, may open the door 38, actuate the lever 41 as described and so detach the clip 34 from the left side of the lower sash and then push rearward the rod 55 to remove the guides from sash holding position. The upper sash may have been lowered so as to be in position to be removed subsequently in its turn and if so its clip 34 will have been removed from the socket 31 at the same time. Or if preferred the upper sash 55 may have been left elevated and so remote from the disconnecting means. The operator then grasps the lower sash and lifts or swings it inward around the right guide channel as a pivot and rests it upon a pad or cushion 61 which may be provided if desired to prevent the marring of the window sill, and to the top of the sash a rod 62 located normally adjacent to the guide 50 may be hooked to the hook 63 so as to relieve the operator from holding the sash in open po-

sition. The sash is then suspended substantially as shown in the diagram of Fig. 7 in such position that the operator may while standing erect within the room polish the outer surface of the pane. After 70 the glass is polished the sash is returned to its normal position and the clip 34 is connected again in place as in Fig. 5 and then this lower sash may be slipped up along the guide channels far enough to lift the cap 21 75 and so clear the top of the upper sash which in turn will be brought forward after its clip 34 is detached for cleansing as just described. The same rod 62 acting upon a hook 63 at the top of the upper sash will 80 act as before described. For maximum ventilation or otherwise both sashes may be removed readily from the window by swinging them forward as just stated and then disconnecting the clips 25 as before described, leaving the sashes free to be lifted down from the window.

The provision of the hollow window frame 11 and access thereto through the door 38 renders it feasible to employ a peculiar sash lock for locking the sashes from relative movement especially when both are closed as in Fig. 11. This locking mechanism comprises a horizontally movable keeper 64 having point or tongue members 90 projectable into a pair of holes or notches 65 and 66 formed in the adjacent portions of the upper and lower sashes respectively. The keeper is rigid and therefore both sashes are positively locked from relative movement. To unlock the window the operator simply projects his hand within the hollow frame and withdraws the keeper from holding position, until a stop 68 is struck, a manipulating handle 67 being provided for this purpose.

I claim:

1. The combination with a window frame, a sash slidable up and down therein, and counterweights connected to the sash, of a connection for one of the counterweights including a socket piece counter sunk in a cavity in the side of the sash and a clip engageable inward and upward into said socket piece for normal engagement, and a detaching dog for said clip normally outward beyond the edge of the sash and movable inward and downward to engage said clip to remove it and hold it in position withdrawn from the sash, said dog being mounted for combined slidable and rotating movement with respect to a fixed pin to cause the same to have a reaching and sweeping movement into engagement with the clip.

2. The combination with a window frame, a pair of relatively slidable co-operating sashes movable up and down therein, and counterweights connected to the respective sashes, of manually operated means at one

side of the window sashes for simultaneously disconnecting both counterweight connections from the adjacent side of both sashes, the mechanism for detaching both 5 connections simultaneously including a rock shaft, a pair of slideable and tiltable dogs having hooks for engagement directly with the weight connections, and a pair of arms extending from the rock shaft and pivotally 10 connected to the ends of the dogs remote from the engaging ends thereof.

3. In a window construction, the combination with a frame having a hollow side, a 15 pair of sashes slideable up and down therein relative to each other, and guiding means for normally holding the sashes in sliding position, of means manually operable from within the hollow side of the frame for withdrawing the guiding means simultaneously 20 from the same side of both sashes to permit said sashes to be brought inward from the frame, said means for withdrawing the guiding means comprising a pair of bell cranks mounted to swing around parallel axes, a rod connected to both bell cranks 25 for swinging them simultaneously, and loose jointed connections between the bell cranks and the guiding means, substantially as set forth.

4. In window construction, the combination with a frame, a pair of sashes movable relatively up and down therein, means to disengage the sashes singly from the frame for removing the same inward therefrom, and means at the top of the frame to permit 35 one of the sashes to move upward above its normal run in order to clear the other sash for the removal of the latter while the former stays in the frame, said means including a horizontal cap member, a pair of arms 40 connected thereto and movable around a horizontal axis at the rear of the cap, and means connected to the cap resisting the movement thereof out of normal position.

5. In a window construction, the combination of a frame having removable guide means, a sash slideable along said guide means, means for removing said guide means to allow the sash to be swung out of the plane of said frame, a hook upon said 50 sash and means attached to said frame co-operating with said hook to retain said sash in substantially fixed position relatively to said frame after being swung out of the plane thereof.

In testimony whereof I affix my signature.

IRVING L. KORROL.
